UNITED STATES PATENT OFFICE.

HARRY F. FISHER, OF ST. PAUL, MINNESOTA.

DWELLING INCINERATOR DOOR.

Original application filed July 26, 1924, Serial No. 728,442. Divided and this application filed April 22, 1926. Serial No. 106,168.

My invention relates to incinerator doors and is particularly adapted to a type of door which has an automatic closing shield to prevent gases and smoke from the chimney entering into the room while the door is open or being opened. This application is a division of my application, Serial Number 728,442, filed July 26, 1924.

10 A feature of my invention resides in a door adapted to be placed in the chimney flue and provided with means whereby the refuse from other incinerator doors cannot become lodged or engaged on the opening of a door below.

15 It is also a feature of my invention to provide an inner closure member which operates automatically to keep the door opening closed on the inner side of the door and to provide a smooth arcuated surface on the 20 flue side of the door opening. This construction provides means whereby when the incinerator door is open to receive the refuse, the rear door means remains closed preventing any gases or smoke entering the

25 room into which the incinerator door opens. Upon closing the door the inner closure is operated automatically at a point just before the closing of the room incinerator door and at a time when the refuse receiving scoop door is closing very rapidly, so that the inner door is only opened momentarily and is operated automatically so that as the scoop door closes in the room, the inner door operates automatically and closes 35 automatically. This is accomplished by lever and cam means associated with the main scoop door of the incinerator door.

40 It is a feature of my invention to provide an inner door which is pivotally connected in a manner so that it will move in closing position by gravity automatically after it has been moved by the closing of the main scoop door which engages a lever fastened to the pivotal connection of the inner door.

45 These features together with other particular formation of my door and the connecting parts will be more fully set forth in the specification and claims.

50 In the drawings forming part of this specification:

Figure 1 is a cross sectional view of the refuse receiving door for incinerators.

Figure 2 is a similar view to Figure 1,

illustrating the scoop door in open position.

Figure 3 is a front view of the refuse or 55 incinerator door.

Figure 4 is a sectional view of Figure 1, illustrating the lever and cam for operating the same. The lever operating member is placed on either end or both ends of the 60 incinerator door.

In the drawings my incinerator or refuse door I is adapted to be placed in the chimney E of a residence or building. The incinerator door I is adapted to be placed 65 in the wall of the building as illustrated in Figure 1 with an opening extending through the wall into the flue lining of the chimney.

My incinerator door I is positioned so 70 that the face plate 30 of the same projects at an angle and is pivoted at 32, a handle 31 being placed at the top or free end of the door of the plate 30 so that the door plate and door can be engaged to open into the 75 position illustrated in Figure 2.

The door I is formed of a scoop like nature with the face plate 30 to which the handle 31 is attached so that the door can be opened easily and is provided with the 80 side plates 33 which are rigidly secured to the face plate 30 in a simple manner. Formed integral with the side plates 33 I provide a bottom member 34 which extends across between the sides 33 and spaces the 85 same apart to provide the scoop like construction to the door I. This scoop like construction of the door I provides a refuse receptacle into which the garbage and other refuse can be discharged when the door I is 90 in open position, as illustrated in Figure 2 of the drawings. The outer edges of the sides 33 are of arcuate shape to form an arc with a radius approximately from the hinging point 32 so that the door I in pivoting permits the sides to slide freely into the opening in the chimney E.

95 The construction of the scoop door I with the face plate and sides 33 together with the bottom 34, provide a scoop like construction 100 to the door which is very adaptable in use and which permits the door to be hinged at 32 in a manner so that when it is substantially in closed position, as illustrated in Figure 1, the bottom 34 of the door I 105 is in line with the bottom 35 of the open-

ing in the chimney E, and at a steep incline so that the refuse in the scoop like door I will be dropped quickly and readily into the chimney flue E. This is also facilitated by the frame which supports the door I at the pivot point 32. This frame work is secured to the chimney in any simple manner and forms the casing around the opening in the chimney and about the door I.

Within the opening extending into the chimney E for the door I, I provide a shutter door 36 which is pivotally secured at 37 and which is formed of an arcuated form so as to fit over the arcuate edges of the sides 33. The door 36 is of a width so as to practically close the opening into which the sides of the door I fit in the chimney or opening, and thus the sides of the door 36 rest against the arcuated sides 33 of the door I when the door I and the shutter door 36 are in closed position, as illustrated in full lines of Figure 1 of the drawings.

The door 36 is adapted to be operated by a lever 38 which is operated by the cam 39 in the closing operation of the door I when the shoulder side of cam 39 comes in contact with the free end 40 of the lever 38.

The lever 38 is pivotally connected to the end of the shaft or pivot point 37 of the door 36 and is formed with a shoulder 41 which engages against the shoulder 42 when the arm 38 is moved by the closing movement of the door I when the cam 39 engages against the free end 40 of the same. The arm 38 however, is free to move or lift upwards into the dotted position illustrated in Figure 2 during the opening operation of the door I and when the cam edge of the cam 39 engages under the free end of the lever 38 at the end 40. This permits the door I to be opened without operating or moving the door 36, the lever 38 lifting up into the dotted position of Figure 2 while the door I opens, and not disturbing the position of the door 36. The door 36 hangs by gravity into closed position illustrated in full lines in Figure 1. When the incinerator door I is moved into closed position, from the position illustrated in Figure 2, the shoulder of the cam 39 engages against the free end 40 of the lever 38 and the shoulder ends of the lever 38 and the sleeve of the door 36 which is pivoted to the rod 37, which are respectively 41 and 42, engage together and cause the door 36 to be opened by the lever 38. This operation is almost instantaneous. As the door I is allowed to slam shut it operates the door 36 to open the same quickly at the end of the stroke or closing of the door I and thus the shutter door is only open momentarily. This permits the garbage or refuse from the scoop incinerator door I to be quickly discharged into the chimney flue E. The slamming of the shutter door 36 which falls into closed

position by gravity after the cam 39 has disengaged the free end 40 of the lever 38, together with the slamming of the incinerator scoop door I causes the refuse in the door I to be discharged readily and prevents it from remaining in the scoop of the door I. This adds materially to the practical operativeness of my door and shutter construction.

It is quite an important feature of my invention in providing the shutter door 36 which keeps all smoke and gases out of the room into which the incinerator scoop door I opens. It is not desirable to have the gases or smoke from the chimney flue E come out into the room while the incinerator door is open and because this has been true of many other constructions of doors, these incinerator doors have been necessarily placed in hallways or other out of the way places. This is not necessary with my door as the shutter door keeps the opening closed at all times and until the incinerator scoop door I is practically in closed position. Then when the shutter 36 is opened it is only momentarily so that the face plate 30 of the door I closes the incinerator door opening almost immediately upon the opening of the shutter 36. I have found this particular door construction for incinerators to be very desirable and much preferred over any door where the shutter is not apparent.

In operation and use my door is very simple and the shutter 36 remains closed throughout the entire opening of the incinerator scoop door I, and as long as the door I remains in open position the shutter 36 remains closed, completely shutting off the gas chamber of the flue E of the chimney of the room in which the incinerator door I opens. Yet when the door I is moved into closed position the shutter 36 is quickly and effectively opened to discharge the refuse into the incinerator flue chimney E. This incinerator flue chimney E is the main flue chimney for the incinerator and for the heating plant in most cases where incinerators are employed and for this reason it will be readily appreciated that the shutter door is of great importance in my invention. The installations of my door have been quite satisfactory in every respect and apparently are being greatly appreciated in the many places where I have had them installed, so that the effective operation of the same is quite complete.

In the drawings I have illustrated the lever operating means 38 attached to either side of the door I and operable with the cam 39 secured to the side plates 33. This causes the effective operation of the shutter door 36. It is quite apparent, however, that only one operating means, such as the lever 38, together with the cam 39 and the shoulders 41 and 42 are necessary to operate the shut-

ter 36 when it is of a small nature, not being of too heavy a construction. On the larger door it may be more practical to use two levers so that the shutter 36 is operated 5 equally on each side. I desire to have it understood that only one operating lever 38 is necessary to raise the door 36 when it is of ordinary light weight construction. The operation is very effective and the incinerator door I gives a very satisfactory 10 result in use. The effect of the shutter in closing the incinerator flue opening E is much desired and greatly preferred to an incinerator door not having this shutter arrangement.

In accordance with the patent statutes I have described the principles of operation of my incinerator scoop door, and while I have illustrated a particular formation in the 20 drawings, I desire to have it understood that these are only suggestive as to the carrying out of my invention and that the invention can be applied to other uses and carried out by other means than those above set forth 25 within the scope of the following claims.

I claim:

1. A door for an incinerator in combination with a chimney connecting with a combustion chamber, a scoop-like door pivotally secured to said chimney, a passage leading from said door into said chimney and a guard-like safety door pivoted in the top portion of the sides forming said door passageway and adapted to be opened automatically 30 upon the closing of said incinerator door.

2. An incinerator door including a scoop-like body portion pivotally secured to an incinerator chimney in a manner to cause the 40 bottom of said scoop-like door to be inclined at a steep downwardly depending angle, arcuate side walls formed on said door, an arcuate guard safety door pivotally secured to lie in close proximity to the arcuate edges 45 of said side walls to close the door opening into said chimney and means for automatically operating said safety door by cam lugs positioned on the side wall of said scoop-like door.

3. An incinerator door including a scoop-like body portion, a handle for operating said door on the face plate thereof, said door being pivoted in a manner to swing into and out of a passageway leading into 55 an incinerator chimney and a safety door pivotally secured in the upper portion of the sides forming said passageway in a manner to be operated automatically by said incinerator door.

4. An incinerator door including a face plate, handle means for operating said door, scoop-like walls having arcuate outer edges, a bottom space between said side walls, a safety guard door pivotally associated with 60 said scoop-like door in a manner to close by

gravity the opening leading from said door into the incinerator chimney to which it is attached, said safety guard door lying in close proximity to said arcuate edges of said side walls and lever and cam operating means adapted to permit said incinerator door to be opened without operating said safety guard door and to automatically operate said safety guard door upon the closing of said incinerator door, which closes by 75 gravity automatically when said incinerator door is closed.

5. An incinerator door including a closure member having a door face plate, said member including a scoop-like means adapted to receive refuse when in open position, and shutter means associated with said scoop-like door means adapted to be automatically opened and closed by the closing of said door on the closing movement only 80 of said door, said shutter closing the gas opening of an incinerator flue while the scoop-like door is in open position.

6. An incinerator scoop-door, means for pivotally holding said door in an incinerator flue opening adapted to extend in an inclined position to discharge the refuse in the same into the incinerator flue opening in closed position, and a shutter adapted to be automatically operated only by the closing of door, said operation of the incinerator door of the shutter taking place at the moment when the incinerator scoop door is practically closed so that the shutter remains open only momentarily.

7. An incinerator closure door including a scoop-like pivoted member adapted to form the closing door of the incinerator door opening, a gas and smoke shutter door associated with said scoop-like door, adapted to hang by gravity into closed position and means for operating said shutter door by said scoop-like door automatically on the closing of the scoop-like incinerator door.

8. An incinerator closure door including a scoop-like member pivotally connected to the opening in an incinerator flue, an arcuate shutter door adapted to hang freely in closed position by gravity to close the flue opening of the incinerator door to prevent gases from coming out of said opening when the scoop-like door is in open position and means for automatically operating said shutter door only on the closing movement 115 of said scoop-like incinerator door.

9. An incinerator door having a scoop-like door construction pivotally secured to an incinerator flue opening, and shutter means adapted to close the flue opening while the door is in open position and means upon said door for opening said shutter by the closing movement of said scoop-like incinerator door.

10. An incinerator door including a

4
scoop-like member adapted to form a door inclosure for an incinerator flue opening, arcuate edges formed on said door, along the sides thereof, a shutter adapted to extend over said edges and close the flue opening to prevent gases coming out of the incinerator flue when the door is open, shutter operating lever means adapted to be operated on the closing of the door momen-

tarily just before the closing position of the 10 door.

11. An incinerator door secured to an incinerator flue opening, a shutter associated with said door normally closing said flue opening and means for opening and permitting automatic closing of said shutter during the closing movement of said door.

HARRY F. FISHER.
